UNITED STATES PATENT OFFICE.

JAMES ROBINSON, OF DAIREN, MANCHURIA.

RADIATOR WRENCH.

Application filed July 10, 1925. Serial No. 42,702.

My invention relates to improvements in wrenches, for assembling and disassembling direct radiators, connected with right-and-left-hand threaded nipples.

5 An important object of the invention is to provide a wrench of the above mentioned character, which may be used in connection with nipples of different sizes, such as one and one-half inch and two inch nipples.

10 A further object of the invention is to provide a wrench of the above mentioned character, which may be used in connection with radiator sections of different lengths.

The radiator wrench, now employed for 15 assembling and disassembling direct radiators, is obtainable in different sizes, depending upon the size of the nipple, such as a one and one-half inch nipple or a two inch nipple. These wrenches are provided at 20 one end only with a head which engages with the flange within the nipple. These wrenches also come in different lengths, depending upon the lengths of the radiator sections, to be assembled and disassembled.

25 In accordance with my invention, I provide a wrench embodying a bar which is provided at its opposite ends with heads of different sizes, for engagement within nipples of different sizes, such as one and 30 one-half inch and two inch nipples. Further, the bar is provided with a turning member or head, longitudinally adjustable thereon, whereby the wrench may be made in the maximum length, and the turning 35 head adjusted longitudinally thereon, as may be found desirable for use in connection with radiator sections of varying lengths.

40 My wrench thus dispenses with the necessity of employing a plurality of wrenches of different sizes and lengths, and is also a great time and labor saver.

In the accompanying drawings forming 45 a part of this specification and in which like numerals are employed to designate like parts throughout the same,

Figure 1 is a plan view of a wrench embodying my invention,

50 Figure 2 is a side elevation of the bar element included in the wrench,

Figure 3 is a side elevation of the device in use,

Figure 4 is a transverse section taken on line 4-4 of Figure 1,

55 Figure 5 is a transverse section on line 5-5 of Figure 3, and,

Figure 6 is a perspective view of a liner.

In the drawings wherein for the purpose of illustration is shown a preferred embodiment of my invention, the numeral 10 designates a relatively long bar, which is made in a length for use with the radiator section having the maximum length, whereby the wrench may be used with radiator sections of shorter lengths. This bar is provided 60 at one end with a nipple turning head 11, and at its opposite end with a nipple turning head 12. These nipple turning heads are of different sizes. The head 11 may be adapted for properly engaging within a one and one-half inch nipple while the head 12 may suitably engage in a two inch nipple. As clearly shown in Figure 5, the head may engage with flanges or projections 13, 65 formed in the nipple 14, which is a right-and-left-hand threaded nipple. As is well known, direct radiators are formed in sections of selected lengths, and these sections are connected by the direct right-and-left-hand threaded nipples. 70

The bar 10 is provided with grooves 15, extending longitudinally throughout the same for the major portion of its length.

The numeral 16 designates a turning head 85 embodying a sleeve 17. This sleeve has a recess for the reception of liners 18. These liners have segmental flanges 19, held within recesses 20 whereby the liners are positively locked against turning movement with respect to the sleeve 17. The liners are held 90 against longitudinal displacement by set screws 21'. The liners 18 are provided upon their inner curved sides with flanges or ribs 21, slidably within the grooves 15. In view 95 of the foregoing description, it will be seen that the sleeve 17 is splined upon the rod, and is free to be shifted longitudinally thereof, but cannot turn with relation thereto. The sleeve 17 is provided with radial sockets 22, formed integral therewith, and these sockets are adapted to receive bars or levers which turn the head. 100

In the use of the device, the head 11 or 12, depending upon the size of the nipple to be turned, is inserted into the radiator section and into the nipple 14. The turning head 16 is then shifted longitudinally of the bar or rod 10, to bring the same into close relation to the outer end of the radiator section. The head 16 is turned by the lever or rod inserted in the sockets 12, as is obvious. 105 110

While it is preferred to equip the turning head with the liners 18, so that they may be replaced, when worn, the invention is of course not restricted to this feature, as the turning head may be splined upon the rod or bar, to turn therewith, and move longitudinally thereof, by any suitable means.

It is to be understood that the form of my invention herewith shown and described is to be taken as a preferred example of the same, and that various changes in the shape, size, and arrangement of parts, may be resorted to without departing from the spirit of my invention or the scope of the subjoined claims.

Having thus described my invention, I claim:

1. A radiator wrench comprising a rigid rod of substantial length provided at its

opposite ends with nipple engaging heads of different sizes, said rod having a groove extending between the heads, a turning head having a bore, and a liner removably mounted within the bore of the head and having a bore to slidably receive the rod, said liner having a part entering the groove.

2. A radiator wrench comprising a rigid rod of substantial length provided at its opposite ends with nipple engaging heads, said rod having grooves extending between the heads for a major portion of the length of the rod, a turning head having a bore, and a two-part liner removably mounted within the bore of the head and having a bore to slidably receive the rod, said liner parts having tongues to enter the grooves.

In testimony whereof I affix my signature.

JAMES ROBINSON.
